Attns.

UNITED STATES PATENT OFFICE.

ERNST ADLER, OF VIENNA, AUSTRIA.

SAFETY RAZOR.

Application filed August 18, 1925, Serial No. 51,010, and in Austria November 10, 1924.

This invention relates to a safety razor in which a substantially flat blade is mounted between a bed plate and a cover plate. The principal objects which the present invention has in view are: to provide such connecting means between the bed plate of the safety razor and its handle, that the latter may be adjusted quickly at any desired angle relatively to the bed plate and consequently to the cutting edges of the razor blade, further an improved device for easily ejecting the blade and a special form of the guard device.

Several embodiments of the invention are shown in the accompanying drawings in which—

Fig. 1 represents in side view partly in section a safety razor with one form of the connection between the handle and the bed plate.

Fig. 2 is a plane view of the same.

Fig. 3 is a front view.

Fig. 4 is a sectional view taken on the line *a*—*b* in Fig. 2.

Fig. 5 and 6 represent modifications of the construction according to Figs. 1-3.

Fig. 7 shows the ends of the handle provided with hemispheres.

Fig. 8 shows the radial grooves in the base of a hemisphere.

In Figs. 1-3 of the drawings 1 is the bed-plate, on one narrow side of which a cover plate 2 is hinged at 3. The inside of this cover-plate is grooved as to form three ledges 5, 6 and 7. From one to the other narrow side of the bed-plate are running two ledges 8, 8' between which pins 9, 10 are inserted to engage corresponding holes of the blade 11.

On the narrow side, of the bed plate opposite to the hinge 3 a tongue 12 is hinged at 13, which extends below the razor blade and lies flush in the bed plate. The tongue 12 carries an outwardly projecting finger 14, whereas on the free narrow side of the cover

plate a locking member 15 is hinged. To make the safety razor ready for use, the blade 11 is put upon the bed plate (Fig. 3), then the cover plate is turned down in the position, shown in Fig. 3 by dotted lines

and the locking member 15 is pulled over the finger 14, in the direction of the arrow *p*, pressing thereby the cover plate against the bed plate.

In order to remove the blade, first the locking member and then the cover plate is turned up. Now a light pressure upon the

finger 14 is sufficient to eject the blade 11 without the slightest danger of wounding or hurting the hands.

The bed plate 1 carries on both long sides instead of the usual guard fingers full bridges 16, 17 provided towards the cutting edges with little protuberances 18 in comb-like intervals with the effect, that the apparatus during the use adheres with a full edge to the skin and not with the separate teeth of the comb, whereby a uniform tension of the skin is secured. Further the hole cutting edge of the blade becomes operative and the hairs are directed towards the cutting edge by the above mentioned protuberances.

On the ends 19, 20 of the bifurcated springy handle 21 hemispheres 22, 23 are formed, the bases of which are provided with radial grooves 24 as shown by Fig. 7, 8. The cross section of these grooves corresponds to the polygonal cross section of a mandril 25, fixed on the underside of the bed plate. In the drawings a square mandril is represented, but the invention is not limited to this form of cross section. Each pair of grooves may surround and hold fast the mandril by the spring force of the bifurcated handle. The mandril is also provided with two pins 26, 27 engaging corresponding holes 28, 29 in the two hemispheres 22, 23. These pins act as pivots when the mandril is turned from one groove to the next and prevent simultaneously the mandril from slipping out of the handle.

According to Figs. 5 and 6 the mandril is fixed obliquely on the bed plate and according to Fig. 5 provided with pins 26, 27 engaging corresponding holes in the hemispheres 22, 23 or as illustrated by Fig. 6 a ball 30 is formed on the mandril engaging hemispherical recesses 31, 32 in the two hemispheres of the handle. By this oblique arrangement of the mandril the bed plate together with the razor blade may be adjusted by turning the mandril in such a position, that the bed plate and the handle intercross one another and that the cutting edge of the razor blade takes the most convenient position for commodious shaving.

By the arrangement of a ball on the mandril engaging ball shaped recesses in the hemispherical ends of the handle a double movement of the bed plate 1 with respect to the handle is possible. In the first place the bed plate may be adjusted obliquely to the

handle or turned down by turning the mandril from one pair of opposite grooves of the hemispheres, 22, 23 to the other, whereby the ball 30 serves as a pivot. Further it is possible to rotate the mandril together with the bed plate in the bearing formed by a determined pair of opposite grooves.

By this latter arrangement it is possible to adjust the cutting edge of the razor blade 10 at any convenient and desired position relatively to the handle, which is held in the hand.

Having thus described my invention, I claim as new and desire to secure by Letters 15 Patent:—

1. In a safety razor an arrangement for adjusting the handle with respect to the bed plate carrying the blade, comprising a mandril of polygonal cross-section secured to 20 the underside of the bed plate, a bifurcated springy handle, hemispheres on the ends of the latter, grooves adapted to the cross-section of the mandril in the base of each hemisphere, one pair of grooves surrounding and holding the mandril in the desired position when the safety razor is in the desired operative position.

2. In a safety razor an arrangement for adjusting the handle with respect to the bed 30 plate carrying the blade, comprising a mandril of polygonal cross-section secured to the underside of the bed plate, a bifurcated springy handle, hemispheres on the ends of the latter, grooves adapted to the cross-section of the mandril in the base of each hemisphere, recesses in the two hemispherical 35

ends of the handle, and extensions on the mandril for engaging the said recesses to prevent the mandril from slipping out of the handle when moving from one groove to another groove.

3. In a safety razor an arrangement for adjusting the handle with respect to the bed plate carrying the blade, comprising a mandril of polygonal cross-section secured at an 45 angle to the underside of the bed plate, a bifurcated springy handle, hemispheres on the ends of the latter, grooves adapted to the cross-section of the mandril radially disposed in the base of each hemisphere, one 50 pair of grooves surrounding and holding the mandril in the desired position when the safety razor is in the desired operative position.

4. In a safety razor an arrangement for 55 adjusting the handle with respect to the bed plate carrying the blade, comprising a mandril of polygonal cross-section secured at an angle to the underside of the bed plate, a bifurcated springy handle, hemispheres on 60 the ends of the latter, grooves adapted to the cross-section of the mandril radially disposed in the base of each hemisphere, recesses in the two hemispherical ends of the handle, and extensions on the mandril for 65 engaging the said recesses to prevent the mandril from slipping out of the handle when moving from one groove to another groove.

In testimony whereof I have signed my 70 name to this specification.

ERNST ADLER.
